UNITED STATES PATENT OFFICE.

CHARLES M. FITCH, OF CHICAGO, ILLINOIS, ASSIGNOR, BY MESNE ASSIGNMENTS, TO BIRD ADDING MACHINE COMPANY, OF CHICAGO, ILLINOIS, A CORPORATION OF ILLINOIS.

ADDING-MACHINE.

1,349,194.

Specification of Letters Patent. Patented Aug. 10, 1920.

Application filed June 25, 1917. Serial No. 176,742.

To all whom it may concern:

Be it known that I, CHARLES MAXIMILIAN FITCH, a citizen of the United States of America, and a resident of Chicago, county 5 of Cook, and State of Illinois, have invented certain new and useful Improvements in Adding-Machines, of which the following is a specification.

This invention relates to adding machines 10 of the type disclosed in patents to Gatewood, No. 789,688, May 9, 1905, and No. 1,123,515, January 5, 1915, and in patent to Sweet *et al.*, No. 1,128,546, February 16, 1915.

The main objects of the invention are to 15 provide adding machines of the type mentioned with improved mechanisms requiring fewer parts and being simpler in action than is the case with the devices shown in said patents; and to provide an improved 20 differential mechanism and an improved carrying mechanism.

An illustrative embodiment of this invention is shown in the accompanying drawings, in which—

25 Figure 1 is a plan view of the device with the cover removed.

Fig. 2 is a fragmentary plan view of the device with the main numeral disk omitted.

Fig. 3 is a transverse vertical section taken 30 on the line A—A of Fig. 1.

Fig. 4 is a side elevation of the hundreds disk or wheel.

Fig. 5 is a detail in elevation of a spring 35 pressed locking device for the hundreds wheel.

Fig. 6 is a sectional detail in elevation, of a support for the transfer pawl and the yoke shown in Figs. 2 and 3.

Fig. 7 is a longitudinal section taken on 40 the line B—B of Fig. 1.

Fig. 8 is a bottom plan view of a ratchet and transfer cam.

Fig. 9 is an enlarged detail in section of the transfer pawl, taken on the line C—C 45 of Fig. 2.

In its main features, the present device 50 comprises a horizontally rotatable numbered disk which is connected to a spring motor normally urging the disk to rotate in a left-hand direction and to progressively exhibit numbers on its upper surface, through a sight opening provided in the cover of the machine. The controlling keys are pivotally mounted on an arc with respect to the center

of said disk and are arranged to release the 55 disk and permit it to rotate under the action of the spring motor until an oscillating member movable with the disk engages the inner end of a depressed key. Adjacent the disk is a higher order wheel arranged to rotate around a horizontal axis and to exhibit its numerals through the same sight opening. Transfer mechanism is provided between the numbered disk and the higher order wheel, which is operative in an adding and 60 subtracting direction, so that it will transfer correctly when amounts are added to the lower order disk and also when the lower disk is reversely rotated to its zero 65 position. In this manner, both disks may be restored to zero, by merely backwardly rotating the spindle which carries the lower order disk. This spindle is connected to the inner end of a spiral spring which constitutes the 70 motor for operating the device. Thus, upon 75 resetting operations, the spring is wound, thereby receiving the required energy for operating the device under the control of the numeral keys.

The operating mechanism of the device 80 is mounted on a sheet metal frame 1 which rests within a flanged base plate 2. The operating keys are pivotally mounted on an arcuate rod 3 which in turn is supported in a frame member 4 secured to the frame 1. 85 The frame member 4 comprises end plates 5 and 6 and a central tie plate 7 connecting the arcuate plates 8 and 9, all vertically disposed. The operating keys 9.1 radiate from the numeral-disk-supporting spindle 10 and 90 are guided in their oscillating motion by slots 11 and 12 in the parts 8 and 9 of the frame 4. The keys are depressible against the action of the springs 12.1, and their rear ends 13 extend beneath an arc-shaped bail 95 14, the parallel arms 15 of which are bent to pass through apertures 16 in the standards or upwardly bent portions 17 of the lower bearing plate 18 of the spindle 10. The plate 18 is secured to the frame member 1. 100 The upper end of the spindle 10 is journaled in a plate 19 which is bent to U-form and is secured to the plate 18 and the frame 1 by the screws 20 (Fig. 1).

The lower order numeral disk 21 is secured to a cylindrical member 22 pinned to the spindle 10 and serving as a hub for the numeral disk 21 and ratchet wheel 23,

thus compelling the numeral disk and ratchet wheel to rotate as a unit when rotary motion is imparted to the spindle 10. For the purpose of receiving motion from 5 and also winding the spring motor 24 (Fig. 3), the spindle 10 carries at its lower end a pinion 25 meshing with a gear 26 fast to the motor spindle 27 to which the inner end of the spring 24 is secured. The outer end of the spring is secured to a post 28.

For the purpose of imparting differential motion to the disk 21 under the control of the keys 9,1, an arm 30 is rotatably mounted on the collar 22 in an annular 15 groove 31 therein. This groove is of rounded or V-form, for the purpose of permitting the arm 30 to oscillate vertically while preventing it from sliding vertically on its journal. The forward end 32 of the 20 arm 30 is loosely curled around the arcuate bar or bail 14. Thus, when a key is depressed and the bail is rocked upwardly, the arm 30 will also swing upwardly, and the arm is provided with a pointed pin 33 25 for entering the adjacent hole of a series of annular perforations 34 in the numeral disk 21.

After the point of the pin 33 has entered one of the perforations in the numeral disk, 30 further upward motion of the bail 14 results in disengaging a pawl 35 (Fig. 2) from the ratchet wheel 23. The means for disengaging the pawl comprises an arm 36 fast to one end of one of the arms 15 of the bail 14. The arm 36 engages a shoulder 37 on the pawl 35 and in this manner rocks the pawl away from the ratchet wheel, around its pivot 38 against the action of the spring 39. The numeral disk then rotates in a forward direction under the action of the 40 spring member 24, and since the pin 33 engages the numeral disk, the arm 30 will be rocked with the disk until it engages the portion 13 of the depressed key. Thus, the 45 angular motion of the disk 21 is determined by the angular position of the depressed key with respect to the spindle 10. If the "1" key is depressed, the disk will rotate only one unit, or one one-hundredth of a rotation, 50 whereas if the "18" key is depressed, the disk will rotate eighteen one-hundredths of a rotation.

The higher order wheel 40 consists of a drum having 10 divisions numbered from 1 55 to 10. This wheel is rotatably mounted on a stub shaft 41 extending inwardly from one of the vertical arms of the bracket-shaped frame member 19. The wheel 40 is normally prevented from rotating by a 60 lug 42 engaging the wheel at one of the ten perforations 43 therein. The lug 42 projects from the lower end of a ring 44 located within the wheel 40 and encircling the stub shaft 41. This ring is mounted to 65 oscillate vertically around a pair of pins

45 extending from the frame 19. The spring 46 normally urges the ring 44 to rock in such direction as to lock the wheel 40.

The transfer mechanism consists of a reciprocating and oscillating member 47 (Fig. 2) having a pointed end 48 adapted to enter one of the perforations 43 in the higher order wheel, either to the right or the left of the perforation which is engaged by the lug 42. The end 48 when entering one of said perforations rocks the ring 44 around the pins 45, disengaging the lug 42 from the wheel 40. The wheel then is under the control of the member 47 and is turned thereby in additive or subtractive direction, one unit for each complete rotation of the numeral disk 21, respectively, on adding or resetting operations. For the purpose of projecting the member 47 into engagement 85 with the wheel 40, a small post 49 projects downwardly from the ratchet wheel 23. This post is in a suitable location to engage the rear end 50 of a slide member 51 at the time the wheel 21 passes from 99 to 0, or 90 from 0 to 99. The slide member 51 is provided with legs 52 resting on the fixed plate 18 between the flanges 53 thereof. The slide 51 is also provided with pins 54 projecting through curved slots 55 in the carrying device 47. Thus on the motion of the slide 51 under the action of the pin 49, the carrying device 47 is projected into engagement with the wheel 40, due to the pins 54 engaging the ends of the slots 55. The 100 transfer device may then oscillate on either one of the pins 54 as the slot 55, engaged by the opposite pin, permits such motion. The transfer device 47 is normally retained in a central position, as shown in Fig. 2, by a 105 spring 56 (Fig. 9) extending between the lug 57 on the transfer device 47 and a screw 58 depending from the slide member 51. The inner end of the transfer device 47 is curved as shown in Fig. 2, and is bent upwardly at 59 for the purpose of co-operating with a semi-spiral actuating cam 60 secured to the lower surface of the ratchet wheel 23. The normal position of the lug 59 being as shown in Fig. 2, the cam 60 will rock the 110 transfer device 47 either to the right or the left, depending upon the direction of rotation of the ratchet wheel. Since in adding operations the ratchet wheel rotates in the direction indicated by the arrow 61 (Fig. 120 2), the lug 59 will be engaged by the inside surface of the cam, and the transfer device, during the rotation of the cam, will be gradually rocked to the left, around the pin 54. When the transfer device is in its extreme left-hand position, the pin 49 projects the transfer device into engagement with the wheel 40, and before the pin 49 clears the inner end of the slide 51, the cam 60 releases the transfer device 47, which then os- 125 130

cillates back to its normal position as shown in Fig. 2. This rocking motion of the transfer device results in the higher order wheel 40 rotating one unit of movement in 5 a forward direction.

On resetting operations, the ratchet 23 is rotated oppositely to the direction indicated by the arrow 61, and therefore the outer surface of the cam 60 engages the lug 59 10 and rocks the transfer device 47 outwardly around the pin 54', and when it releases the same, permits it to return to its normal position and rotate the wheel 40 backwardly one unit for each complete backward rotation 15 of the wheel 21.

In resetting the device, backward rotation is imparted to the spindle 10 by means of the crank handle 62, which has a slotted hub 63 formed to engage a transverse pin 20 64 in the upper end of the spindle. Since the disk 21 and ratchet wheel 23 are fast to the spindle, the wheel 21 is rotated backwardly, and the transfer device operated for each backward rotation of the numeral 25 wheel 21 to impart one unit of backward motion to the higher order wheel 40. When the latter wheel arrives at zero position, the disk 21 will also be at zero position, and further backward motion is prevented 30 by an arm 65 engaging the spindle 10. The arm 65 is fast to a pinion 66 rotatably mounted on the stub shaft 67, which is driven one tooth space for each complete rotation of the spindle 10 in either direction, 35 by a pin 68 projecting from the spindle in the horizontal plane of the pinion 66. The arm 65 therefore may be rotated in either direction until stopped by engagement with the spindle 10, and determines the maximum 40 amount which may be accumulated by the numeral wheels, and also prevents rotation of such wheels beyond the zero position upon resetting operations. The retaining pawl for the pinion 66 is indicated at 66.1.

45 In the operation of the device, assuming that each of the numeral wheels indicates zero, a depression of the key will result in rocking the arcuate bar 14 upwardly, thereby causing the pointed pin 33 to engage one of the perforations 34 in the numeral disk 21. The arm 30, being capable of rotation around the spindle 10, may then rotate with the numeral disk 21 under the action of the spring motor 24 until said arm is stopped by 50 engagement with the rear end 13 of the depressed key. The motor is permitted to act only after the pin 33 has engaged the disk 21, by reason of the fact that the pawl 35 (Fig. 2) is disengaged from the ratchet 55 wheel 23 by the arm 36 fast to the arcuate bar 14, only after the pin 33 has entered one of the perforations 34. Upon the release of the depressed key, the pawl 35 again engages the ratchet 23, thus preventing 60 further rotation of the disk 21 under the 65

action of the motor. As the arcuate bar 14 returns to normal position, it disengages the pin 33 from the disk 21, due to the fact that the outer end of the arm 33 is loosely curled around the bar 14. As amounts are 70 successively added to the numeral wheel 21, the cam 60 serves to rock the transfer device 47 around its pivot 54, in a left-hand direction. The transfer device is then projected into one of the apertures 43 in the 75 higher order wheel, by the pin 49 engaging the slide 51 upon which the transfer device is mounted. When the numeral wheel 21 arrives at zero position, the lug 59 of the transfer device clears the end of the 80 cam 60, and the transfer device rocks back to normal position under the action of its spring 56, and through its pointed end 48 causing 1 to be added to the higher order wheel. Further forward rotation of the 85 disk 21 as controlled by the numeral keys 9.1 causes the pin 49 to clear the inner end of the slide 51, which then returns to its 90 normal position, carrying with it the transfer device 47 under the action of the spring 51.1. The slide 51 is guided in its reciprocating motion by the fixed plates 18 and 18.1.

The device may be reset to zero at any 95 time, merely by rotating the spindle 10 in a right-hand direction (Fig. 2), by means of the crank handle 62. In this direction of rotation of the spindle, the teeth of the ratchet 23 idly ride over the end of the pawl 35. Each time the disk 21 passes the 100 zero point, the transfer device will be operated in a subtractive direction, due to the return rocking motion of the transfer device under the action of its spring 56 when it is released by the cam 60, which upon 105 resetting operations, normally serves to rock the transfer device to the right (Fig. 2). When the higher order wheel arrives at zero position, the arm 65, by engaging the spindle 10, prevents further rotation of the 110 pinion 66, and consequently, rotation of the numeral wheels beyond their zero position.

Although but one specific embodiment of this invention has been herein shown and described, it will be understood that numerous details of the construction shown may be altered or omitted without departing 115 from the spirit of this invention as defined by the following claims.

I claim:

1. A device of the class described, comprising a numbered rotatable disk, a spring for rotating said disk, a ratchet wheel rigid with said disk, a pawl for engaging said ratchet wheel and normally preventing rotation of the disk under the action of the spring, an arm arranged to oscillate around the axis of said disk and to rock vertically into and out of engagement therewith, and manipulative devices adapted to disengage 125

4
said pawl from the ratchet and limit the rotation of the numbered disk by coöperating with said arm.

2. A device of the class described, comprising a numbered rotatable disk, a spring for rotating said disk, a ratchet wheel rigid with said disk, a pawl for engaging said ratchet wheel and normally preventing rotation of the disk under the action of the spring, an arm arranged to oscillate around the axis of said disk and to rock vertically into and out of engagement therewith, a pivoted bail for rocking said arm vertically, said bail being arranged to rock the pawl out of engagement with the ratchet wheel, and keys radially arranged with respect to the axis of said numbered disk and adapted to rock said bail and limit the rotation of the disk by coöperating with said arm.

3. A device of the class described, comprising a numbered rotatable disk, a spring for rotating said disk, a ratchet wheel rigid with said disk, a pawl for engaging said ratchet wheel and normally preventing rotation of the disk under the action of the spring, an arm arranged to oscillate around the axis of said disk and to rock vertically into and out of engagement therewith, a pivoted bail for rocking said arm vertically, said bail being arranged to rock the pawl out of engagement with the ratchet wheel, and manipulative means adapted to rock said bail and limit the rotation of the disk by coöperating with said arm.

4. A device of the class described, comprising a lower order numeral wheel and a higher order numeral wheel, means for differentially rotating the lower order wheel, a transfer device, a slide upon which said transfer device is pivotally mounted, an open spiral cam rigid with the lower order wheel arranged to rock said transfer device around its pivot in a direction dependent upon the direction of rotation of said lower order wheel, means for shifting said slide to engage the transfer device with the higher order wheel, and means for rocking the transfer device around its pivot back to normal position.

5. A device of the class described, comprising a lower order numeral wheel and a higher order numeral wheel, means for differentially rotating the lower order wheel, a transfer device, a slide upon which said transfer device is pivotally mounted, an open spiral cam rigid with the lower order wheel arranged to rock said transfer device around its pivot in a direction dependent upon the direction of rotation of

said lower order wheel, means for shifting said slide to engage the transfer device with the higher order wheel, and a spring for rocking the transfer device around its pivot back to normal position.

6. A device of the class described, comprising a lower order wheel and a higher order wheel, a spring motor arranged to drive said lower order wheel, manipulative means for controlling the rotation of the lower order wheel under the action of said spring motor, carrying mechanism between said lower and higher order wheels, said carrying mechanism comprising an oscillating pawl for engaging the higher order wheel, a slide upon which said pawl is mounted, said slide being shiftable under the action of said lower order wheel, and a double pivotal connection between said pawl and slide, said lower order wheel being arranged to oscillate said pawl around one or the other of the slot and pin connections with said slide according to the direction of rotation of said lower order wheel, and a restoring spring extended between said slide and pawl.

7. A device of the class described, a numeral disk, a spring motor for driving said disk, keys radially arranged with respect to the center of the disk and adapted to regulate its motion under the action of the spring motor, a higher order wheel, and means for effecting carrying operation from said numeral disk to the higher order wheel, said means comprising a pawl having a pair of curved slots, a slide provided with pins extending through said curved slots, said disk being provided with means for reciprocating said slide, said disk also being provided with means for oscillating said pawl on one or the other of said pins in accordance with the direction of rotation of said disk, and a restoring spring extended between said slide and pawl.

8. A device of the class described, comprising a numbered rotatable disk, a spring for rotating said disk, a ratchet wheel rigid with said disk, a pawl for engaging said ratchet wheel and normally preventing rotation of the disk under the action of said spring, a pivoted bail arranged to rock said pawl out of engagement with said ratchet wheel, and manipulative means adapted to rock said bail to shift said pawl out of engagement with said ratchet wheel and to limit the rotation of the numbered disk under the action of said spring.

Signed at Chicago this 2nd day of June, 1917.

CHARLES M. FITCH.
